Primary Examiner—Cathron C Brooks*Assistant Examiner*—Deanna Fluegeman(74) *Attorney, Agent, or Firm*—Banner & Witcoff, Ltd.(57) **CLAIM**

The ornamental design for a user interface for a display screen, as shown and described.

DESCRIPTION

The FIGURE is a front view of a user interface for a display screen showing the new design.

The broken line showing of the display screen and the broken line showing of the portions of the user interface are included for the purpose of illustrating unclaimed environment and form no part of the claimed design.
